PHILIP ROLLHAUS, OF PORT CHESTER, NEW YORK.

Letters Patent No. 96,839, dated November 16, 1869.

COOKING-RANGE.

The Schedule referred to in these Letters Patent and making part of the same.

To all whom it may concern:

Be it known that I, PHILIP ROLLHAUS, of Port Chester, in the county of Westchester, and State of New York, have invented a new and improved Elevated Oven-Range; and I do hereby declare that the following is a full, clear, and exact description thereof, which will enable others skilled in the art to make and use the same, reference being had to the accompanying drawings, forming part of this specification, in which—

Figure 1 represents a plan or top view of my improved elevated oven-range.

Figure 2 is a vertical transverse section of the same, the plane of section being indicated by the line z z , fig. 1.

Similar letters of reference indicate corresponding parts.

This invention relates to a new manner of arranging the pipes between the water-back and the boiler, with an object of allowing them to be made with a short turn, to enable the use of brass pipes. Heretofore, on the ordinary elevated oven-ranges, the pipes were made of wrought-iron, as they had to be so much bent that cast-metal could not be employed. They were, therefore, liable to corrode, and were, moreover, difficult to reach when injured or stopped.

My invention consists, first, in providing an opening in the stove-plate, and a lid or cover for said opening. Thereby the ends of the pipes, where they are connected to the water-reservoir, can be easily reached.

The invention relates, also, to a novel appliance for withdrawing the dust from the lower fire-chamber, while the fire is being raked, so that a lively fire can, at all times, be kept up.

For this purpose, I arrange a self-closing damper, on a dust-pipe, in rear of the fire-box, the said pipe serving to direct the draught, while the fire is being attended to, while otherwise, it is closed by the damper.

A, in the drawing, is the lower tier of an elevated oven-range.

B is its top plate.

C is the water-back or reservoir, arranged in rear of the fire-chamber D.

E are the pipes, projecting from the water-reservoir, to conduct the water to the boiler.

These pipes are, by right and left-hand nuts, a a , coupled to the reservoir, and are then each, by a single turn, bent sideways, to lead directly to the boiler.

In the plate B is an aperture, b , closed by a lid, c , directly above the nuts a .

Through this aperture, the nuts can, at any time, be reached, and the pipes put on or taken off, as may be desired.

Heretofore, without the opening b , the pipes had to be carried forward to the side of the range, in order to be within reach, and were, therefore, so curved, that they could only be made of wrought-iron.

My pipe can now be made with but one knee or bend, and can, therefore, be cast of brass, and much expense will be saved, besides preventing the corrosion of the pipes.

In rear of the range is a vertical flue, F, which is open on top, and flush with the top of the fire-box and water-reservoir, while its lower end extends into the ash-chamber G.

This lower end is automatically closed by a self-closing damper, H, which is pivoted at its upper part, and which is connected with a lever, I, that extends to the front of the range. By pulling the said lever, the damper will be opened; but when the lever is let go, the damper will at once be closed.

When the fire is raked the damper should be opened, so that the fine ashes raked down may, by the draught, be carried up through the flue F, to be deposited on the top of the water-back C; also, when on the said top, a large quantity of dust has collected, it may be swept into the flue, and the damper then opened, to discharge the matter into the ash-pan.

Having thus described my invention, I claim as new, and desire to secure by Letters Patent—

The plate B, covering the lower tier of an elevated oven-range, and provided with an aperture, b , through which the pipes E can be reached, substantially as herein shown and described.

PHILIP ROLLHAUS.
